(57) **CLAIM**

The ornamental design for an ANTI-THEFT NUT as shown and described.

DESCRIPTION

FIG. 1 is a perspective view of an ANTI-THEFT NUT, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

The broken lines in the drawings show portions of the ANTI-THEFT NUT which form no part of the claimed design.

1 Claim, 6 Drawing Sheets
